UNITED STATES PATENT OFFICE.

JOHN LOUIS SCHNEIDER, OF CHARLES CITY, IOWA.

OIL HOLDER.

Application filed July 27, 1925. Serial No. 46,414.

This invention relates to improvements in dispensing means to be applied upon the quart size Ball and Mason fruit jars which in this instance are to be filled with lubricating oil in order that the said oil may be readily and easily dispensed from the said jar.

Another object of my invention is the provision of a handle attached to the jar and jar cap while the cap further includes 10 a spout connected therewith and including a closure cap upon its outer end operated by an operating rod arranged upon the handle portion in order that the said closure cap may be readily and easily opened when the 15 said jar is inverted and the spout inserted within the breather cap opening provided in the motor vehicle crank case, not shown.

With the above and other objects in view, the invention further includes the following 20 novel features and details of construction, to be hereinafter more fully described, illustrated in the accompanying drawing and pointed out in the appended claim.

In the drawing:—

25 Figure 1 is a fragmentary vertical section of my invention when so applied to a Ball or Mason jar.

Figure 2 is a sectional view of the outer free end of the spout and closure cap.

30 Figure 3 is a fragmentary top plan view of the spout and closure cap.

Referring to the drawing in detail, wherein like characters of reference denote corresponding parts, the reference character 10 35 indicates either the pint or quart size of the well known Ball or Mason fruit jars having the usual and conventional form of jar top 11 arranged upon its neck; all of the above is of the usual and well known construction and forms no part of the present application for Letters-Patent but is merely shown for purposes of illustration in bringing forward the novel advantages of the above entitled invention.

45 The invention residing in the provision of a tube 12 having its lower end communicating with the upper side and within the upper side of the jar top 11 and within the jar 10 and set at an inclination thereto, as 50 clearly illustrated in Figure 1 of the drawing, which includes upon its outer end and adjacent the rearward side thereof, a pair of spaced parallel apertured ears 13 having a pin 14 extending therethrough and 55 supporting an ear 15 carried upon the inner side of the closure cap 16 while a spring 17

encircles a portion of the pin 14 and engages the upper side of the ear 15 whereby the said cap 16 will be normally held in a closed position. In order to provide holding or supporting means for the jar 10 in the form of a handle I provide ravelings of 60 wire terminating in loops 19 and 20 upon their upper and lower ends; the upper loop 19 is received within the depressed portions formed by the thread upon the inner side of the jar top 11 while the lower loop 20 is slidingly received upon the lower portion of the jar 10.

For facilitating the opening and closing 70 of the closure cap 16 included upon the outer free end of the spout 12, I provide a clamp 21 arranged upon the wire ravelings and to which a bell crank lever 22 is pivotally supported thereon and which terminates at its outer end in a disk 23 adapted to be engaged by the thumb of the user when grasping the wire ravelings forming the handle. A rod 24 has its ends pivotally secured to the inner free end of the bell crank lever 22 and 75 its upper end correspondingly secured within an aperture 25 provided upon one side of the closure cap 16.

In the mode of operation of the present 80 invention it is clearly apparent and manifest that the jar top 11 and handle formed by the wire ravelings 18 may be unscrewed as a unit from the jar 10 when refilling the same. When it is desirous to add to the oil 85 already contained within the crank case or to entirely replenish the supply therein when draining the old oil, and owing to the fact that the breather caps, not shown, upon various types of automobiles are frequently 90 inaccessible owing to the mountings of distributor heads, throttle rods and the like which interfere with the filling of the crank case at this point, namely the breather cap, I have provided this novel form of dispensing 95 apparatus which, owing to the inclination 100 of the spout 12 upon the jar top 11, may be readily and easily inserted within a breather cap and centrally therein while the closure cap 16, included upon the outer free end of the said spout or tube 12, may be 105 readily and easily opened and closed by the operator's thumb when engaging the disk 23 included upon the outer free end of the bell crank lever 22.

It is further to be noted that owing to the 110 simplicity of construction and arrangement of parts thereof that the same may be manu-

factured in great numbers and consequently sold at a very nominal cost owing to the fact that no special form of container is sold with the device in so far as the said Mason or Ball type of fruit jars are obtainable in every jurisdiction.

The invention is susceptible of various changes in its form, proportions and minor details of construction, and the right is here-
10 in reserved to make such changes as properly fall within the scope of the appended claim.

Having described my invention what is claimed is:—

15 In a dispensing device for jars, the combination with a jar having an externally

threaded mouth and provided with a cap having a threaded engagement with said mouth, of a handle formed of twisted wire to provide a closed ring at one end engaging 20 around the threaded wall of the jar cap and a ring at its other end rotatably engaging around the body of the jar, a spout extending from the jar cap, a spring actuated closure for the outlet end of the spout, a bell 25 crank actuator operatively supported upon the handle remote from the closure and a rod connecting the closure and bell crank actuator, whereby pressure upon the bell crank actuator will open the closure.

In testimony whereof I affix my signature.

J. LOUIS SCHNEIDER.
